UNITED STATES PATENT OFFICE.

WILLIAM R. ARNOLD, OF GENEVA, NEBRASKA.

STACK-ROOF.

1,278,559.

Specification of Letters Patent. Patented Sept. 10, 1918.

Application filed November 14, 1916. Serial No. 131,299.

To all whom it may concern:

Be it known that I, WILLIAM R. ARNOLD, a citizen of the United States, residing at Geneva, in the county of Fillmore and State 5 of Nebraska, have invented new and useful Improvements in Stack-Roofs, of which the following is a specification.

The present invention relates to improvements in means for erecting sheds or the like 10 that are primarily, but not necessarily, devised as a protective covering for hay and grain stacks, feed racks and the like.

The primary object of the invention is to produce a device of this character wherein 15 the boards or plates may be easily, quickly and securely connected without the employment of nails or analogous securing elements, and wherein the edges of the boards or plates will lap to provide a perfect shed 20 for water, etc., and whereby to provide a covering that will effectively prevent the contents thereof from the elements.

In carrying out my invention it is my purpose to produce stringer members of flexible 25 material, such as strips of wire, to bend the ends of the same upon themselves whereby the first board or plate of the cover may be thus secured to the stringers, and to provide hooks of a novel construction which may be 30 easily and quickly arranged upon the stringers to support the remaining boards or plates of the cover.

It is a further object of the invention to produce an adjustable stack roofing chain 35 whereby boards or plates of varying widths may be easily, quickly and securely attached and wherein all of the boards or plates will have their edges lapping.

It is a still further object of the invention 40 to produce a stack roofing chain which may be arranged either upon the interior or upon the exterior of the roof and which will effectively support the boards or plates of the roof when the chain is in either of such positions.

An additional object is the provision of a stack roof of this character which may be partially or even entirely assembled while 45 lying flat upon the ground and which may subsequently be grasped at its ends by two operators and positioned over a stack to be roofed without the necessity of either operator climbing upon the stack itself.

With the above and other objects in view

the improvement resides in the construction, 55 combination and arrangement of parts set forth in the following specification and falling within the scope of the appended claims.

In the drawing:

Figure 1 is a perspective view of a stack 60 roofing constructed in accordance with the present invention,

Fig. 2 is a sectional view through the same taken in a line with one of the chains,

Fig. 3 is a transverse sectional view upon 65 an enlarged scale approximately on the line 3-3 of Fig. 2,

Fig. 4 is a perspective view of one of the stringer members of the chain, and

Fig. 5 is a similar view of one of the hook 70 members for the chain.

While my improvement may be employed in the construction of buildings, such as sheds or the like, and which structure may be either of a temporary or permanent nature, the improvement is primarily designed, 75 as illustrated in the drawing, to facilitate in the erection of roofing or covering members for grain or hay stacks, the device being particularly useful in this direction inasmuch as the covering can be easily and quickly applied to effectively protect the stack against the elements and as easily and quickly removed from the stack, when occasion requires. Furthermore, the construction is such that the boards or plates forming the covering may be piled one upon the other, when the device is not in use, to occupy only a comparatively small space for transportation or storage, and wherein the 80 chain construction may be likewise folded and arranged in the same package with the boards or plates.

In carrying out my invention I employ 85 any desired number of stringer members 1-1. Each of the members 1 is preferably constructed from a single strand of suitable wire and has its opposite ends bent upon itself and continued in a line with the main strands, as indicated by the numerals 2, 100 whereby to receive the end boards or plates 3, or whereby the hooks provided by the bent portions 2 may be associated so that the stringers may be of any desired length. The flexible stringers are, of course, adapted 105 to be arranged around the stack 4 which is to be protected by the covering, and in order to insure the stability of the device flexi-

- ble elements, such as auxiliary wires, may be passed through the stack at the bottom thereof and have their ends secured to the bent ends or hooks 2 of the stringers 1.
- 5 After the end or face boards 3 are arranged upon the stringers, as described, I insert upon each of the stringers a hook 5 that is adapted to overlie the upper edges of the boards 3. All of the hooks employed 10 in my improvement are of a similar construction, but, of course, the same may vary in proportion in accordance with the boards or plates with which they are adapted to engage.
- 15 Each of the hooks 5 is preferably constructed from a single strand of wire and includes a looped portion 6 that is adapted to engage with the stringer 1. The arms of the loop 6 are bent angularly thereof, as indicated by the numeral 7, the said bent portions 7 being in parallelism and the ends of the said portions 7 are bent outwardly, as at 8, in a line parallel to the arms of the loop and are from thence continued upwardly to provide the outer spring members 9. It will thus be noted that the body of each of the hook members is substantially U-shaped in side elevation, each of said sides being similar, but, of course, spaced 25 away from each other, and this construction is particularly desirable as the spaced members of each of the hooks provide for the ready insertion of said hooks over the stringers 1, as will, it is thought, be perfectly understood, and furthermore, the outer members 9 of the hooks are adapted to exert a tension inwardly toward the member 7 thereof, whereby to compress therebetween the edges of the boards or plates 10. Again the U-shaped element of the said hooks provides means whereby the edges of the boards comprising the roofing will overlap thus effectively shedding rain or moisture therefrom and consequently protecting the stack from the elements.

An important feature of this device is that a partial or even the entire assembling of the parts may be accomplished while the stringers and boards are lying flat upon the 50 ground and that the entirely or partially assembled roof may be grasped at the ends by two operators and bowed upwardly for disposition over a stack without the necessity of either operator climbing upon the 55 stack itself. Furthermore, it will be noted that the device when disassembled may be very easily and conveniently stored away and will occupy but slight space.

It is, of course, to be understood and as 60 clearly illustrated in the drawings, the hooks 5 upon the opposite sides of the stack are reversely positioned and while two of such

reversely positioned hooks might be employed for securing the edges of the central or top board or plate, and while such 65 an arrangement might be particularly desirable especially when the top of the roof is in the nature of a bendable member, such as a thin metal plate, I have found it desirable to centrally secure to the stringers 70 1 a tie wire 11 and to bring the said wire around the plate or board next to the top plates or boards and to twist the ends of said wire 11 over the said top boards or plates, as clearly illustrated by the drawings, and by this means it will be noted that the top boards or plates have their edges overlapping the boards or plates adjacent thereto.

Having thus described the invention, what 80 I claim is:

1. A stack roof comprising a plurality of boards disposed in arcuate form and arranged with the lowermost edge of each board in overlapping relation to the uppermost edge of the next adjacent board, a horizontally disposed top board having its side edges disposed in overlapping relation to the upper edges of the adjacent boards 85 at both sides thereof, a plurality of flexible 90 stringers disposed upon the undersides of said boards and having their lower ends bent outwardly and upwardly in encircling relation to the lowermost boards, the extremity of each stringer being coiled upon 95 itself above the top edge of the lowermost board, and a plurality of hooked members straddlingly and slidably engaged upon said stringers, and engaged beneath the lower edges of said boards.

2. A stack roof comprising a plurality of flexible stringers, spaced boards associated with the ends of the stringers, the end of each stringer being bent upon itself into encircling relation to the associated board and having its extremity coiled upon itself and a plurality of other boards detachably connected with said stringers and arranged in overlapping relation to said first named boards and to each other.

3. A stack roof comprising a plurality of flexible stringers each bent upon itself at its end to provide a loop and having its extremity coiled upon itself, boards disposed within said loops, and a plurality of other boards detachably connected with said stringers and disposed in overlapping relation to said first named boards and to one another.

In testimony whereof I affix my signature. 120
WILLIAM R. ARNOLD.
